UNITED STATES PATENT OFFICE.

WILLIAM F. BURNS, OF MEMPHIS, TENNESSEE.

AUTOMATIC ELECTRIC WINDOW GUARD.

Application filed May 24, 1922. Serial No. 563,462.

To all whom it may concern:

Be it known that I, WILLIAM F. BURNS, a citizen of the United States, and residing at Memphis, in the county of Shelby and 5 State of Tennessee, have invented certain new and useful Improvements in Automatic Electric Window Guards, of which the following is a specification.

This invention relates to automatic electric window guards, or apparatus for use in connection with display windows, and the primary object thereof is to provide an appliance of this class designed particularly for use in connection with the display windows of merchants, or traders dealing in 10 jewelry, precious stones, furs or light merchandise, and which is particularly designed to prevent the theft or stealing of such merchandise by the breaking, cutting out or 15 otherwise removing a portion of the window and the insertion of a hand therethrough.

It is a well known fact that in the use of display windows of the class specified, valuable jewelry, precious stones and the like 20 are within easy reach of any person who breaks or cuts out a portion of the glass, and a further object of this invention is to provide a guard which will be thrown into protecting position and prevent the removal 25 of the merchandise in the window upon breakage of the glass.

A still further object is the provision of a 30 guard for display windows which will be operated by electrical means, upon the breakage of the glass of said window.

Another object of the invention is to provide means on the glass of the display window whereby upon breakage of the glass one 35 electrical circuit is broken and another circuit simultaneously made whereby the guard is thrown into protecting position.

Further objects and advantages of this invention will be apparent from the following specification when taken in conjunction with 40 the accompanying drawings forming a part thereof.

In the drawings:

Figure 1 is an elevation of the device, partly in section shown with a display 45 window;

Fig. 2 is an end view, in section, of the device applied to a display window;

Fig. 3 is a fragmentary view, partly in 50 section of the device in elevated position;

55 and

Fig. 4 is a detail sectional view of a por-

tion of the device in raised position showing the retaining means therefor.

Referring more particularly to the drawings, 1 indicates the glass of a display window, which is secured within the usual frame 2; the display window having a floor 3 and being supported by the customary base or foundation 4.

Secured to the frame 2, at each side thereof, is a channel bar 5, the lower ends of which extend below the floor 3 of the window as will be seen in Figs. 1 and 2.

The grating is composed of a lower cross bar 7, an upper cross bar 10 and uprights 8 65 secured together as shown in the drawings.

The lowermost end of each channel bar 5 is provided with a seat 6. Said seats serve to support the ends of the cross bar 7 of said grating, which has wire mesh or the like 9 secured thereto in any suitable manner. The upper cross bar 10 of grating has 70 its ends retained within the channel bars 5 as will be obvious.

Secured to the grating 8 at opposite sides 75 thereof are rack bars 11 and 12, respectively, said rack bars having the teeth removed at the lower ends thereof for a substantial distance, as shown at 12'.

Mounted beneath the floor 3 of the window in any suitable manner and substantially midway of the grating is an electric motor 13 having outwardly extending shafts 14, mounted in bearings 15, said shafts carrying near their ends pinions 16, which 80 pinions mesh with the upper ends of rack bars 11 and 12.

As shown more clearly in Figs. 2 and 4, the floor 3 of the window is provided with an opening 17 extending substantially the 85 entire length of the window and normally covered with a gate 18 hinged at 19 to said floor 3, the gate being formed preferably of sheet metal or the like.

For the purpose of retaining the grating 100 in elevated position a spring pressed stop 20 is provided which is secured in any suitable manner to the base 4, as illustrated in Fig. 4, said stop being adapted to expand and support the grating by receiving the 105 lower end of one of the uprights 8 of the grating when the grating is in elevated position.

The numeral 21 denotes a conductor secured to the glass 1 and forming part of a 110 control for relay circuit, conductor 21 being tinfoil or the like. It is obvious that suit-

able advertising may be employed as a conductor as is well known in the art.

A wire 22 leads from one end of conductor 21 to a battery 23 (the positive side thereof), 5 and the other end of conductor 21 is connected to one terminal 24 of a relay 25, by a wire 26. The other terminal 27 of the relay is connected to the battery 23 by a wire 28.

The control circuit just described, it is 10 obvious, is as follows: From the battery 23 through 22, thence through 21 to 26, through relay 25 and its terminals 24 and 27, and back to the battery through wire 28.

Associated with this device is a magnetic 15 contactor of customary construction having terminals 29, terminals 30 and a switch arm 31, the circuit through said contactor being as follows: From the battery 23 through wire 22 to wire 32, thence through terminals 20 29, wires 33 and 34, through terminals 35 of relay 25, and back to the battery through wires 36 and 28.

When the circuit just mentioned is thrown 25 into operation, as will be hereinafter described, the switch arm 31 of the magnetic contactor will contact with terminals 30 thereof, and bring into operation the main or power circuit, which is as follows: From the battery 23 through wire 37 to, and 30 through switch 38 (which latter in the inoperative position of the grating normally holds the main circuit closed), then through wire 39 to the motor 13, from the motor through 40, then through terminals 30 and switch arm 31, back to the battery through 35 wires 41 and 28.

A circuit is associated with this device which is adapted to set into operation an 40 audible alarm such as a bell or the like 42, the circuit therefore being as follows: From the battery 23 through 37 and 43 to the bell 42, from the bell through 44 to the terminals 35 of the relay 25 and back to the battery through 36 and 28.

In normal position, the grating is 45 retained as shown more clearly in Fig. 2, and should the glass 1 be broken or a piece crossed by conductor 21 removed therefrom in any manner the control circuit above 50 mentioned will be broken, it is obvious, thus permitting arm 45 of the relay 25 to drop and contact with terminals 35 which will set into operation the circuit through the other magnetic contactor, which latter circuit 55 will place switch arm 31 of the magnetic contactor into contact with terminals 30.

Upon this latest operation the motor 13 will be energized because of the fact that the

main or power circuit will be brought into 60 operation. At this time the audible alarm will be sounded due to the circuit thereof.

Upon the starting of the motor, which in reality results primarily from the breakage of the glass 1, the shafts 14 will be rotated with their pinions 16, the rotation of said 65 pinions serving to elevate the grating due to the connection of rack bars 11 and 12 therewith. When the grating has been raised into protecting position, a detail of which is shown in Fig. 3, the push button of 70 switch 38 will engage in a recess 46 at the lower end of rack bar 11, and the motor circuit will be broken and the motor stopped.

When the grating is being elevated into 75 protecting position the upper edge thereof will strike gate 18 and swing the same on its pivot 19. When the grating has reached its uppermost position, the teeth of the rack bars 11 and 12 will be out of mesh with the teeth of pinions 16, and the grating will be 80 retained in elevated position by the expansion of the spring pressed stop 20 which will engage the lower end of the uprights 8.

After the motor circuit has been broken 85 and the motor stopped, the audible alarm circuit is still in operation, and the alarm being sounded to warn outsiders of the fact that the window glass 1 has been tampered with.

What I claim is:

1. An automatic guard for display windows, comprising a grating movable within said window, a motor for moving said grating, a control circuit, a power circuit connected to said motor, means for setting into operation the power circuit upon breaking of the control circuit, and automatic means for breaking the power circuit.

2. An automatic guard for display windows comprising a vertically movable 100 grating, rack bars secured thereto, a motor connected with said rack bars and adapted to elevate said grating, a control circuit connected with the glass of the display window, a power circuit connected with said motor and adapted to be brought into operation upon the breaking of the control circuit, automatic means for breaking the power circuit upon the elevation of said grating, means for retaining the grating in elevated 105 position, and an audible alarm circuit adapted to be brought into operation upon the breaking of the control circuit.

In testimony whereof I affix my signature.

WILLIAM F. BURNS.
